UNITED STATES PATENT OFFICE.

ARCHIBALD B. TRIPLER, OF PHILADELPHIA, PENNSYLVANIA, ASSIGNOR
TO CHARLES E. TRIPLER.

IMPROVEMENT IN PRESERVING WOOD FOR RAILROAD-TIES, &c.

Specification forming part of Letters Patent No. 104,917, dated June 28, 1870; reissue No. 4,837, dated March 26, 1872.

DIVISION A.

To all whom it may concern:

Be it known that I, ARCHIBALD B. TRIPLER, formerly of New Orleans, in the State of Louisiana, but now of the city and county of Philadelphia and State of Pennsylvania, have invented a new and useful Method for Preventing the Rot or Decay of Railroad-Ties, &c.; and I do hereby declare that the following is a full, clear, and exact description of the same, which will enable those skilled in the art to carry out my invention.

In an application for Letters Patent of even date herewith, I have described and claimed the construction of a railroad-tie composed of two or more slabs or laminae, united together firmly by dowel-pins, whereby a tie is produced ready to be laid in position on the road-bed, while it possesses facility of repair and an elasticity not possessed by the ordinary solid tie.

My present invention looks to the preservation of a railroad-tie thus constructed; and it consists in immersing the slabs composing it in a solution of antiseptic agents, to be hereinafter named, and afterward subjecting it to a bath of coal-tar and powdered charcoal, by which the said slabs are thoroughly impregnated with a preservative, while, when they are united, interior partitions or walls of antiseptic material will insulate each slab, effectually preventing atmospheric decomposition, fermentation, or dry-rot.

The antiseptic which I have used is composed of the following and in about the proportionate parts herein given, though I do not confine myself to its use specially, but purpose using any other antiseptic agent I may elect.

Coal-pitch or asphaltum, parts,	80
Sulphur, parts,	5
Arsenic, parts,	5
Coal-tar, parts,	5
Powdered charcoal, parts,	5
	—
	100

After the slabs composing the tie are subjected to the bath of antiseptics above stated, they are firmly united together by dowel-pins which have also been submitted to the action of preservative agents. Thus a tie is produced having all of its constituent parts preserved, and that, too, in a much shorter time and in a more thorough manner than by any system heretofore adopted, while the tie itself possesses advantages not possessed by any other.

- Having described my invention, I claim—
- 1. Ties, bed-sills, &c., to be preserved from decay, made in sections or slabs, and secured together, for the purpose and in the manner herein described.
- 2. In a tie or bed-sill made in sections or slabs, the intervention of partition or division walls of antiseptic or preservative agents between their adjacent sides, as herein described.
- 3. The method herein described of preserving timber from decay.

ARCHIBALD B. TRIPLER.
